R. S. BOHANNAN

EASER JOINT

Filed Sept. 26, 1925

UNITED STATES PATENT OFFICE.

ROBERT S. BOHANNAN, OF BIRMINGHAM, ALABAMA, ASSIGNOR TO H. M. BARRETT, OF BIRMINGHAM, ALABAMA.

EASER JOINT.

Application filed September 26, 1925. Serial No. 58,927.

My invention relates to an easer rail joint adapted to bridge a track joint from a stationary to a movable section of the track, so as to prevent pounding from the passing 5 wheels.

The chief objects of my present invention are to design seats for the easer rail which are standard and available for use on right or left hand, at either end of the rail, and 10 which are adapted to support the rail so as to avoid the necessity of cutting away part of the tread of the track rails. My invention will be best understood by reference to the accompanying drawings, which illustrate 15 the preferred embodiment of my invention, and in which:

Figure 1 is a plan view of a portion of one line of track rails equipped with my invention.

20 Figure 2 is a side elevation of Figure 1.

Figure 3 is a sectional end elevation of the rail and the easer joint and a portion of a wheel and its axle.

Similar reference numerals refer to similar parts throughout the drawings.

As illustrated, "1" designates a stationary approach rail, and "2" an aligned movable rail, which, in the present instance, is a scale rail. (The crosstie supports and the scale 30 are omitted for the sake of clearness.) An easer bar "3", which serves to bridge the joint between the rails "1" and "2", has sloping ends "4" leading upwardly towards its center portion, which is disposed at break joints 35 with the rails "1" and "2" and with its tread level slightly above the level of said latter rails. The easer bar is provided at one end with a hole for the reception of a bolt "5", which is adapted to pass through a slot in a 40 cast-steel riser block "6" and through the rail "1".

The riser block "6" is formed with an upwardly-opening, elongated channel or recess "7" making it U-shaped in transverse cross- 45 section and has reversely sloping bottom walls "8" and "9" interposed between an outer vertical web "10" and an inner vertical web "11", which latter is adapted to fit snugly between the tread and base of the rail "1", with the bottom wall of the block resting on the base of the rail "1". The outer and inner webs are provided with inclined slots "12", parallel with the adjacent bottom walls "8" and "9", and it is through 50 these slots that the bolt "5" passes to secure

one end of the easer rail in position on the riser block.

When the apparatus is being assembled, the riser blocks 6 are spaced apart a sufficient distance so that the ends of the easer 60 bar 3, where they rest on the inclined faces 8 and 9, are raised sufficiently to bring the tread of the easer bar slightly above the tread of the rail 1. This spacing varies with the size of the rail with which the bar is associated. The easer bar 3 is made of hardened steel, with the holes already provided in the ends thereof, so that by making the slots 12 parallel with the inclined faces 8 and 9 of the riser block 6, the holes in the 70 ends of the easer bar always lie opposite the slots 12, whatever the linear adjustment of the riser blocks. The riser block wall "11" carries end flanges, which are secured by bolts "13" to the web of the rail "1", and the 75 base of the riser block is adapted to receive spikes or anchor bolts through the holes "14", which will secure it in position. The cast-steel riser block at the other or far end of the easer bar, is an exact duplicate of that 80 already described. It is obvious that by adjusting the spacing between the riser blocks, the easer bar can be raised or lowered so that it will work with the various standard sizes of track rail, and by having the reverse 85 bevels at each end it is obvious that only a single standard riser block is required to be stocked.

In operation, having mounted the riser blocks the proper distance apart and drilled 90 a hole through the web of each of the rails "1" and "2" for the bolts "5", and also having drilled the webs of said rails to receive the bolts "13", the blocks are anchored in position, the easer bar is dropped in place and 95 the bolts "5" inserted through the holes in the pivoted ends of the bar and through the slots and rails, and is made secure. The device is then ready for service and will, as shown in Figure 3, engage the tread of the 100 wheel "15" and ride it over the joint between the rails "1" and "2" and ease it down onto the scale rails "2" without harming such rails or damaging the scale.

What I claim is:

1. An easer rail appliance for relatively 105 movable aligned rails of tracks, comprising duplicate riser blocks, shaped at one side to inter-fit with the adjacent track rail, and having an open slot disposed parallel with 110

the rail and offset from the sides of the tread thereof, said slot having reversely inclined bottom walls and side slots parallel with said bottom walls, an anchor bolt passing through the slot and the web of the track rail, an easer bar seated on the reversely inclined bottoms of spaced riser blocks, and having one end secured in position by said bolt to hold its tread alongside the tread of the track rails, and bridging the joint between them.

2. An easer rail appliance for a joint between a stationary and a movable track rail, comprising riser blocks adapted to be rigidly attached to the sides of the adjacent rail ends, beveled seats in said riser blocks adapted to support an easer bar alongside the unchanged tread of the adjacent rails, said easer bar having beveled tread ends and having at one end a hole and a bolt adapted to pass through said hole and anchor said bar and a riser block to the adjacent rail end.

3. An easer rail appliance for aligned rails, one of which is movable downwardly with respect to the other, comprising a pair of duplicate riser blocks snugly fitting against the web and flanges of the respective rails, inclined supporting faces provided on the riser blocks and off-set from the side of the rail treads, and an easer bar pivotally mounted alongside the respective rails in position to bridge the space between the rail ends and resting on the inclined supporting faces.

4. An easer rail appliance for aligned stationary and movable rails, comprising a pair of duplicate riser blocks, U-shaped in cross-section, with the bottoms of the U-shapes inclined downwardly, said riser blocks each

having one side snugly fitting the recess

formed by the web and flange of the associated rail, and being attached thereto, and an easer bar disposed alongside the rails and bridging the space between the riser blocks and resting on the inclined bottoms of the 45 riser blocks.

5. An easer rail appliance for aligned stationary and movable rails, comprising a pair of duplicate riser blocks, U-shaped in cross-section, with the bottoms of the U-shapes inclined downwardly, said riser blocks each having one side snugly fitting the recess formed by the web and flange of the associated rail, and being attached thereto, an easer bar disposed alongside the rails and bridging the space between the riser blocks and resting on the inclined bottoms of the 50 riser blocks, and means for pivotally connecting the ends of the easer bar to the webs of the rails through the riser blocks.

6. An easer rail appliance for aligned stationary and movable rails, comprising a pair of duplicate riser blocks, U-shaped in cross-section, with the bottoms of the U-shapes inclined downwardly, said riser blocks each 55 having one side snugly fitting the recess formed by the web and flange of the associated rail, and being attached thereto, an easer bar disposed alongside the rails and bridging the space between the riser blocks and resting on the inclined bottoms of the 60 riser blocks, and means for pivotally connecting the ends of the easer bar to the webs of the rails through the riser blocks.

7. An easer rail appliance for aligned stationary and movable rails, comprising a pair of duplicate riser blocks, U-shaped in cross-section, with the bottoms of the U-shapes inclined downwardly, said riser blocks each 65 having one side snugly fitting the recess formed by the web and flange of the associated rail, and being attached thereto, an easer bar disposed alongside the rails and bridging the space between the riser blocks and resting on the inclined bottoms of the 70 riser blocks, means for pivotally connecting the ends of the easer bar to the webs of the rails through the riser blocks, and inclined

slots provided in the riser blocks parallel to the inclined bottoms thereof for positioning the pivoted connection.

In testimony whereof I affix my signature.

ROBERT S. BOHANNAN.
